UNITED STATES PATENT OFFICE.

EMERSON F. WYLIE, OF PHILADELPHIA, PENNSYLVANIA, ASSIGNOR TO UNITED SHOE MACHINERY COMPANY, OF PATERSON, NEW JERSEY, A CORPORATION OF NEW JERSEY.

TURN-SHOE.

1,169,710.

Specification of Letters Patent. Patented Jan. 25, 1916.

Application filed October 19, 1910. Serial No. 587,944.

To all whom it may concern:

Be it known that I, EMERSON F. WYLIE, a citizen of the United States, residing at Philadelphia, in the county of Philadelphia and State of Pennsylvania, have invented 5 certain Improvements in Turn-Shoes, of which the following description, in connection with the accompanying drawing, is a specification.

10 This invention relates to the manufacture of shoes and has for its object to improve turn shoes and facilitate certain steps in making such shoes. As is well understood, turn shoes are assembled, pulled over, lasted 15 and sewn while they are wrong side out and are then turned to present the upper on the outer side and the lining on the inner side of the shoe. When the uppers of such shoes comprise a vamp and a tip, or have an ornamental line of stitches to represent the tip 20 line, the tip seam is of course hidden from view by the lining in the pulling-over operation during which the upper is adjusted upon the last preparatory to being fastened 25 to the sole. When these shoes were pulled over and lasted by hand the workman was enabled by the sense of feeling while he held the shoe in his hand to ascertain the position of the tip seam and thus to adjust the upper 30 so that the tip seam would come in the finished shoe in approximately the desired location. The fact that the lining hid the tip seam from view was therefore of minor importance to him, although considerable skill 35 and judgment were required to obtain uniform length of tip and position of the tip seam in such work. More recently, since these turn shoes have been pulled over and lasted by the use of machines, the fact that 40 the tip seam cannot be seen has proven a serious embarrassment, particularly because it is desirable to avoid the delay required for the operator to feel of the shoe which is supported in the machine.

45 In accordance with the present invention, provision is made for rendering the tip seam position of a turn shoe visible to the operator while the shoe is in the pulling-over, lasting or other machine. To this end the 50 lining is provided with markings to indicate the position of the tip seam in the shoe up-

per. These markings may be of any desired character but, as herein shown for exemplification, they are formed by extending the tip seam stitches through the lining. 55

The invention will be more fully explained in connection with the accompanying drawing and will then be pointed out in the claims.

The drawing represents a perspective 60 view of a turn shoe prepared in accordance with this invention to be pulled over.

2 indicates the usual sole of a turn shoe, 4 being the upper and 5 the tip which is joined to the vamp portion of the upper by one or 65 more lines of stitches 6 which constitute the so-called tip seam.

8 indicates the lining which, in accordance with this invention, is marked to indicate visually to the workman, while the shoe is 70 yet lining side out, the location of the tip seam. This marking, indicated at 10, is here represented as made by extending the stitches of the tip seam through the lining. In practice the tip seam marking on the 75 lining is made when the vamp and tip are stitched together if the tip seam is to constitute the marking. It is obvious that instead of so doing any special mark may be applied to the lining at any convenient time, said 80 marking being so located and of such a character as will indicate visually to the workman the position of the tip seam in the upper and enable him in pulling-over and lasting the shoe to adjust the upper so that the 85 tip seam will be presented in the desired angular and longitudinal relation in the finished shoe.

That improvement in methods of making shoes herein disclosed is not claimed in this 90 application but forms the subject-matter of a divisional application, Serial No. 9,976, filed February 23, 1915.

Having explained the nature of this invention, what I claim as new and desire to 95 secure by Letters Patent of the United States is:—

1. In a turn shoe, an upper, a lining and a tip assembled with the lining outside the upper for attachment to the sole of the shoe, 100 said parts having means penetrating the lining and visible on the outer side of the

lining adjacent to its bottom edges at the tip seam line in position to indicate the location of the tip line of the upper in order to facilitate adjustment of the shoe materials upon the last in the pulling over operation.

2. In a turn shoe, an upper and a lining assembled with the lining outside the upper for attachment to the sole of the shoe, said parts having a row of tip seam stitches extending through the lining in position to in-

dicate visually the location of the tip line in the pulling-over operation.

In testimony whereof I have signed my name to this specification in the presence of two subscribing witnesses.

EMERSON F. WYLIE.
